(57) **CLAIM**

The ornamental design of a device holder for a stationary bicycle frame as shown and described.

DESCRIPTION

A portion of the disclosure of this patent document contains material which is subject to copyright protection. This patent document may show and/or describe matter which is or may become trade dress of the owner. The copyright and trade dress owner has no objection to the facsimile reproduction by anyone of the patent disclosure as it appears in the Patent and Trademark Office patent files or records, but otherwise reserves all copyright and trade dress rights whatsoever.

FIG. 1 is a top, right, perspective view of the device holder for a stationary bicycle frame, shown in a condition of use;

FIG. 2 is a top, right, perspective view of the device holder for a stationary bicycle frame of FIG. 1, shown removed from the frame for clarity of disclosure;

FIG. 3 is a bottom, left, perspective view thereof;

FIG. 4 is a right side thereof;

FIG. 5 is a left side thereof;

FIG. 6 is a front plan view thereof;

FIG. 7 is a rear plan view thereof;

FIG. 8 is top view thereof; and,

FIG. 9 is a bottom view thereof.

The broken lines shown represent unclaimed subject matter

and form no part of the claimed design.

1 Claim, 9 Drawing Sheets
